[57] **CLAIM**

The ornamental design for a lace element for a shoe upper, as shown and described.

DESCRIPTION

FIG. 1 is an elevational view of a lace element for a shoe upper showing my new design;

FIG. 2 is a cross section view taken along line 2—2 of FIG. 1;

FIG. 3 is a cross section view taken along line 3—3 of FIG. 1;

FIG. 4 is a cross section view taken along line 4—4 of FIG. 1; and,

FIG. 5 is a top plan view thereof.

The broken line showing of a shoe upper or a portion thereof in FIGS. 1 and 5 is for illustrative purposes and forms no part of the claimed design.

FIG. 5
